UNITED STATES PATENT OFFICE.

WILLIAM G. BROWNE, OF KINGSTON, NEW YORK.

DESIGN FOR A CAN-OPENER.

SPECIFICATION forming part of Design No. 32,875, dated June 26, 1900.

Application filed May 9, 1900. Serial No. 16,097. Term of patent 14 years.

To all whom it may concern:

Be it known that I, WILLIAM G. BROWNE, a citizen of the United States, residing at Kingston, in the county of Ulster and State of New York, have invented and produced a new and original Design for Can-Openers, of which the following is a specification.

This design consists in a can-opener having the top of its fulcrum part concaved in the direction of its length, while the lower part or bottom face of said fulcrum part is convexed in the direction of length, the front edge and bottom of the fulcrum part being curved or concaved in a transverse direction.

The design is illustrated in the annexed drawings, in which—

Figure 1 is a side elevation of a can-opener embodying this design. Fig. 2 is an inverted plan view of Fig. 1. Fig. 3 is a plan view of Fig. 1.

The can-opener is shown with the blade or knife 1, and for convenience of description the face 2 of the fulcrum part facing toward

the blade is called the "bottom" of the fulcrum part, while the opposite face or edge 3 is called the "top" of the fulcrum part. The top 3 of the fulcrum part is concaved or bends upwardly or away from the blade, while bottom face 2, as seen, is convexed. The front edge of the fulcrum part is thrown into a curve 4, extending transversely. The curves 2 and 3 extend longitudinally or in the direction of length of the blade or fulcrum part.

The design presents a striking, ornamental, and characteristic appearance.

What I claim as new, and desire to secure by Letters Patent, is—

The design for a can-opener substantially as herein shown and described.

In testimony whereof I have hereunto set my hand in the presence of two subscribing witnesses.

WILLIAM G. BROWNE.
